UNITED STATES PATENT OFFICE.

CHARLES A. AHLSTROM, OF JAMESTOWN, NEW YORK.

MUSIC-ROLL FOR MECHANICAL MUSICAL INSTRUMENTS.

1,149,317.

Specification of Letters Patent.

Patented Aug. 10, 1915.

Original application filed April 6, 1914, Serial No. 829,864. Divided and this application filed July 27, 1914. Serial No. 853,319.

To all whom it may concern:

Be it known that I, CHARLES A. AHLSTROM, a citizen of the United States, residing at the city of Jamestown, in the county 5 of Chautauqua and State of New York, have invented certain new and useful Improvements in Music-Rolls for Mechanical Musical Instruments, of which the following, taken in connection with the accompanying 10 drawings, is a specification.

The invention relates to music rolls for mechanical musical instruments such as piano players and the like, and the present improvement is a divisional application of 15 the construction shown in the application filed April 6th, 1914, Serial No. 829,864; and the object of the improvement is to provide spools for the note sheets in the roll box of a mechanical musical instrument 20 having shafts which taper from the middle portion toward both ends to draw the note sheet in true alinement upon said spools by the draw of the sheet on the enlarged middle portions; and the invention consists in the 25 novel features and combinations hereinafter set forth and claimed.

In the drawings, Figure 1 is a front elevation of the spool or music roll cabinet of a player piano with both the upper and 30 lower spools therein tapering from the central portion toward each end, the upper spool and the music sheet rolled thereon being shown in lengthwise section to show the enlarged circumference of the central portion 35 of the spool shaft in comparison with the ends and the straight music sheet roll. Fig. 2 is a lengthwise sectional view of the shaft of the lower spool showing its tubular construction with the flanged ends thereon 40 and the annular central groove. Fig. 3 is a lengthwise sectional view of an upper spool, showing a modification of the construction whereby the enlargement of the central portion of the shaft is attained by 45 means of a tapered strip of paper which is wound about the shaft thereby gradually enlarging the central portion, the wider end of the strip being first wound about the shaft and finishing with the narrow end.

50 Like numerals of reference refer to corresponding parts in the several views.

The numeral 10 designates the shaft of an upper music spool, and the numeral 11 the shaft of the lower music spool, which 55 shafts may be turned from wood, this ma-

terial being preferred for the lower shaft 11, or made of some light form of tubing like metal, wood fiber, or paper pulp, which may be given the central enlargement 12 and diminishing taper 13 toward each end. 60

The shafts 10 and 11 have the central enlargement and tapered ends to cause the note sheet 14 to run truly in line with said shafts as said note sheet winds onto the same, the main drawing points being the enlarged central portions 12, so that the tapered ends 13 do not in anywise interfere with or draw upon the music sheet 14 and thereby gradually draw it out of line as it is rapidly 65 rolled upon the spool. 70

The enlargement 12 of the upper spool is preferably formed in the body of the tube by gradually tapering each of the ends 13 from the central enlargement 12. Said tapered ends 13 are preferably given a fairly 75 straight taper while the central portion 12 is given a slight equal curve extending an equal distance each way from the middle of the shaft so as to receive and draw truly upon the music sheet 14. The enlarged portion 12 on the lower spool extends out each way from the central attaching groove 15 within which the hook 16 is placed for attaching the end of the music sheet 14 to the 80 lower roll 11. 85

Each of the spools 10 and 11 are provided with flanged ends 17 which are formed with projecting portions 18 fitting within the ends of the tubular shafts 10 and 11. The lower spool is sometimes a fixed part of 90 the spool box 19, that is, it is not made removable, but it is usually preferred that it should be removably mounted within the spool box 19 so that it may be quickly taken therefrom the same as the top roll either 95 for repair or for insertion in another player without rerolling. The upper spool is usually removably mounted in the spool box 19. The two spools are so arranged on each side of the tracker bar 20 that the music sheet 14 draws truly over said tracker bar as it draws from the enlarged central portion 12 of one spool to the enlarged central portion 12 of the other, thereby holding the music sheet in perfect alinement between 100 the flanged ends 17 as it is obvious that the central enlargement is the same on the lower spool 11 as on the upper spool 10 even though the enlargement is each side of the annular groove 15 on spool 11. 105

In the modification shown in Fig. 3, a straight tube 21 is built up around the periphery of its central portion, the tapered enlargement of said central portion being attained by means of a tapered strip of paper or other material 22 which is wound around the tube 21 preferably beginning with the widest end of the strip and finishing with the narrow end, the gradual taper of the strip being proportioned to the circumference of the shaft 21 so as to give the desired gradual enlargement from the ends to the central portion of the spool shaft. Such a built up construction serves a fair purpose in forming a cheap spool, though it is usually preferred to mold or turn the peripheries of the shaft even though they may be built up, since they will draw more correctly upon the music sheet 14.

The note sheet 14 is attached to the upper spool shaft 10 preferably by means of a flexible strip around the central enlargement and to the lower spool shaft 11 by means of the hook 16, thereby attaching the note sheet at both ends central of its lengthwise portion to the central enlargements of the shafts so that whether winding or rewinding the note sheet draws true to both the upper and lower spools and the tapered ends 13 do not in anywise bind or misdirect the note sheet 14 in rewinding, there being a space 23 between the inner wrap of the note sheet 14 and the periphery 13 around the ends of the shafts 10, 11 or 21. It is apparent that the curve of the centrally enlarged portion 12 is important since it must be exactly the same on both sides of the center of the shaft otherwise the note sheet would not wind onto the shaft in line with the same. It is, however, much easier to give a true curve to the central portion than to make the entire shaft exactly true and the central draw upon the note sheet over the enlargements 12 permits of greater freedom in the mounting of the spools since if said central portions are in line with one another it is not so important as to the remainder of the spools.

The end flanges 17 are inserted in the preferred tubular shaft construction shown without other attachment than the fit of said ends within the tubes and the ends of the tubular shafts form stops for the end flanges 17, the round projecting portions 18 of the end flanges 17 forming a strong attachment between the tubular shafts 10 or 11 and the end flanges 17. The tubular shafts 10 or 11 are made longer than the width of the note sheet 14 so that the ends of the tubular

shafts 10 or 11 form a positive inward stop for the end flanges 17. This arrangement of the end flanges 17 in combination with the enlarged central portion 12 and tapering ends 13 of the shafts 10 and 11 forms a simple and durable spool construction which gives perfect freedom to the edges of the note sheets as they are rolled thereon.

It is apparent that since the enlarged central portion of the shaft of the music roll causes the music sheet to stack or roll evenly thereon and in line with said shaft as it is rolled upon the same, the end flanges 17 may be dispensed with for some purposes, their only office being in controlling the music sheet when it is loose or entirely without tension on the spool shaft.

I claim as new:

1. A music roll spool comprising a shaft of largest diameter at or near the central portion and tapering toward both ends from said central portion to cause the music sheet to draw in true alinement thereon.

2. A music roll spool comprising a shaft of largest diameter at or near the central portion and tapering toward both ends from said central portion to cause the music sheet to draw in true alinement thereon, and end flanges for said shaft.

3. A music roll spool comprising a shaft having a centrally enlarged portion and tapering toward both ends, attachment for the note sheet to said centrally enlarged portion of said shaft to draw in alinement therefrom, and end flanges for said spool shaft.

4. A music roll spool comprising end flanges, a shaft between said flanges, and means for building up the central portion of the outer periphery of said shaft to provide a central enlargement and tapered ends to give a central draw on the music sheet in rolling and rerolling.

5. A music roll spool consisting of end flanges, a shaft between said flanges, and a tapered strip attached around the central portion of said shaft to provide a central enlarged portion for said shaft and give a central draw on the music sheet in rolling and rerolling.

In testimony whereof I have affixed my signature in the presence of two witnesses:

CHARLES A. AHLSTROM.
